DESIGN FOR A TROWEL

Otto Hoffman, Portland, Oreg.

Application October 26, 1945, Serial No. 123,227

Term of patent 14 years

(Cl. D35—2)

To all whom it may concern:

Be it known that I, Otto Hoffman, a citizen of the United States, residing at Portland, in the county of Multnomah and State of Oregon, have invented a new, original, and ornamental Design for Trowels, of which the following is a specification, reference being had to the accompanying drawing, forming part thereof,

I claim:

The ornamental design for a trowel, as shown.

OTTO HOFFMAN.
